UNITED STATES PATENT OFFICE.

LOUIS HACHENBERG, OF NEW YORK, N. Y.

MOTOR FOR STARTING ENGINES.

1,241,625.

Specification of Letters Patent.

Patented Oct. 2, 1917.

Application filed August 31, 1916. Serial No. 117,830.

To all whom it may concern:

Be it known that I, LOUIS HACHENBERG, a citizen of the United States of America, residing at New York, N. Y., have invented 5 a new and useful Motor for Starting Engines, of which the following is a specification.

This invention has reference particularly to motors for starting internal combustion 10 engines and the general objects of the invention are to provide a simple, practical and economical motor for this purpose.

A special object is to provide a construction operable by fluid under pressure which 15 will be powerful in action, simple to build and thoroughly efficient in its operation.

According to the at present preferred form of the invention I construct a motor with a pair of oscillating fluid pressure 20 cylinders disposed on opposite sides of the motor and arranged to operate a power shaft which carries a clutch element for co-operation with a companion clutch element connected with the engine to be started.

25 A special feature is the provision of the oscillating cylinders and the support on which they are mounted with sliding valve faces having coöperating ports.

Another special feature is the making of 30 the support for the cylinders in the form of a casing completely inclosing the cylinders and the provision of one of the walls of the casing with proper passages for the actuating fluid. These passages comprise grooves 35 in the outer face of the rear wall, said grooves being covered by a removable plate.

Various other features of the invention will appear as the specification proceeds, attention being now directed to the accompanying drawings forming part hereof and 40 wherein I have illustrated a concrete and practical embodiment of the invention.

In these drawings:

Figure 1, is a front view of the motor with 45 the walls of the motor broken away and the cylinders within the casing appearing in section, the sectional portion of this view being taken substantially on the plane of the line 1—1 of Fig. 3.

50 Fig. 2, is a view of the opposite or rear side of the machine with the cap plate broken away to show the ports and passages for supplying and exhausting the actuating fluid.

55 Fig. 3, is a cross sectional view taken sub-

stantially on the plane of the line 3—3 of Fig. 1.

Fig. 4, is a broken side view of the motor with the controlling valve shown in section as on the line 4—4 of Fig. 2.

Fig. 5, is a horizontal transverse sectional view of one of the motor cylinders taken in the plane of one of the ports therein.

The base or support for the cylinders is in the form of a casing 7 having for convenience of assemblage a removable front wall 8 and a relatively fixed or integral rear wall 16.

The cylinders are designated 9 there being two of them in the machine illustrated disposed at opposite sides of the power shaft 10 and adapted to work at about an angle of ninety degrees with respect to each other. These cylinders are each provided with oppositely disposed journals 11 and 12 intermediate opposite ends of the same which have a rocking fit in bearings 13 in the opposite walls of the casing.

The admission and exhaust of actuating fluid is governed by a sliding valve action 80 between each cylinder and the adjacent supporting wall, said cylinders having for this purpose, in the illustration, raised valve faces 14 adjacent opposite ends of the same engaging corresponding raised valve faces 85 15 on the rear wall 16 of the casing as shown in Fig. 3. Combination inlet and exhaust ports 17 open from the opposite end portions of the cylinder out through the flattened valve faces 14 thereat, said ports being 90 shown as flared at the mouths thereof as indicated at 18 and registering in the oscillating movements of the cylinders with the properly spaced inlet and exhaust ports 19 and 20 in the valve faces 15 on the wall of 95 the casing.

A proper sliding fit of the valve faces is insured in the case illustrated by a spring 21 bearing against a shoulder 22 on the pivot 100 12 of these cylinders so as to force the cylinders over toward the supporting wall which has the valve faces thereon. These springs serve to take up any wear and they are adjusted as to tension, in the present instance, by means of screw bushings 23 surrounding 105 the reduced outer end portions 24 of the pivots 12 and forming abutments for the outer ends of the springs.

The actuating fluid, which may be steam, compressed air or the like is supplied in the 110

present instance by a conduit 25 having branches 26 communicating with supply passages 27 provided in the valve wall 16, which passages communicate with the inlet ports 19. The exhaust ports 20 communicate with exhaust passages 28 provided in the valve wall 16, said passages having exhaust outlets 29.

A very simple and practical method of providing the exhaust and supply passages is to form these passages as open grooves in the outer face of the wall 16 and then to apply a cap plate 30 to said wall covering said grooves.

15 Pistons 31 are provided in the cylinders, said pistons being connected with the power shaft 10 by means such as piston rods 32 engaging a crank pin 33 on the shaft.

The means for coupling the starting motor 20 to the engine comprises, in the structure shown, a toothed clutch disk 34 slidably keyed on the power shaft 10 and adapted to be shifted by a pivoted lever 35 into engagement with a correspondingly toothed clutch disk 36 on the opposed engine shaft 37, said engine having the usual fly wheel as indicated at 38. By thus coupling the starting motor directly to the engine shaft I am able to utilize the inertia of the fly wheel after 30 the motor has started to turn the engine.

A suitable control valve is provided and the same is herein indicated at 39 located in the supply conduit 25 and provided with a stem 40 connected to a control lever 41. 35 This control lever is shown pivoted at 42 on a bracket 43 and provided with an arm 44 connected with the upper end of a clutch shifting lever 35.

By the construction just described the control lever both operates the control valve and the clutch and the parts are preferably proportioned somewhat as indicated so that the control lever will first slightly open the valve and admit pressure to the cylinders before 45 engaging the two clutch members. This enables the movable clutch member to more readily "find" and pick up the teeth of the companion clutch member.

The moving parts of the motor are wholly 50 inclosed and so are easy to lubricate and are protected from injury. The structure disclosed is particularly desirable for motor boats since the shaft 10 is disposed at the lowest portion of the motor in position to be 55 conveniently coupled to the engine shaft which as well known is located as low as possible in the boat. The motor is simple, very compact and provides for its size considerable power with the further advantage 60 that it starts turning the engine gradually and not with a sudden jerk.

By connecting the supply conduit with the

exhaust outlets 29 it will be obvious that the motor may be rotated in the opposite direction. The flare given to the mouths of the 65 cylinder ports provides a certain amount of "lead" which causes the motor to start easier and operate smoothly at high speed.

When the engine starts under its own power it turns over faster than the starting 70 motor thereby causing the inclines on the teeth of the engine clutch member working against the inclines on the starting motor clutch member to throw back the movable clutch element, disengaging the clutch members and closing off the fluid pressure supply. As the control valve moves to closed 75 position the fluid pressure exerts its force to close the valve and to hold the valve closed against its seat.

What I claim is:

A starting motor comprising a motor casing open at the front and having integral side and rear walls, said fixed rear wall having open inlet and exhaust channels extending across the upper part of the outer exposed face thereof and open inlet and exhaust channels extending across the lower part of the outer exposed face thereof, said fixed rear wall further having inlet ports 90 extending from said inlet channels through to the opposite inner face of the rear wall and exhaust ports adjacent the inlet ports and extending from the exhaust channels through to the inner face of the rear wall, a 95 cover plate removably secured to said rear casing wall and covering the open channels therein, said cover plate having inlet and exhaust ducts therein communicating with the inlet and exhaust channels respectively, 100 raised valve faces on the inner side of the fixed rear wall and through which the inlet and exhaust ports extend, a front wall for the casing closing the open front of the casing and removably secured in place, a crank 105 shaft in the lower central portion of the casing journaled between the fixed rear wall and the removable front wall, a pair of cylinders within the casing above the crank shaft and at opposite sides of the same and 110 provided with trunnions intermediate the ends thereof, journaled between the fixed rear and removable front walls, said cylinders each having raised valve faces on the side thereof adjoining the rear casing wall 115 and bearing on the valve faces on said rear wall, each of said cylinders further having ports at the opposite ends thereof extending directly through the side wall of the cylinder and through to the valve faces thereat, in 120 position to register with the inlet and exhaust ports, and pistons in the cylinders connected with the crank shaft.

LOUIS HACHENBERG.
